UNITED STATES PATENT OFFICE.

JACOB S. MERKINS, OF GRAND JUNCTION, COLORADO.

AUTOMATIC TYMPAN-GAGE.

1,399,141.

Specification of Letters Patent.

Patented Dec. 6, 1921.

Application filed December 27, 1920. Serial No. 433,265.

To all whom it may concern:

Be it known that I, JACOB S. MERKINS, a citizen of the United States, residing at Grand Junction, in the county of Mesa and State of Colorado, have invented certain new and useful Improvements in Automatic Tympan-Gages, of which the following is a specification, reference being had to the accompanying drawings.

10 This invention relates to automatic tympan gages.

An important object of the invention is to provide a tympan gage for use in platen presses whereby a minute adjustment of the 15 paper may be made upon the platen.

In the operation of platen presses equipped with automatic feeders of the Miller type the shifting fork which positions the paper against the side guide, particularly if it happens to exercise too great a grip on the paper, often forces the paper against the side guide to such an extent that the paper when released by the fork "bounces" away from the side.

25 An important object of this invention, therefore, becomes to provide means for overcoming the bounce of the paper. This I accomplish by having a side guide which is shiftable and which engages the paper

30 and shifts the same in the opposite direction to which it is shifted by the fork a sufficient distance to overcome the tendency to bounce, the engagement by the side guide being subsequent to the engagement by the shifting fork. A further object of the invention is to provide an improved construction of the side guide and to provide an 35 adjustable mounting for the side guide support.

40 Other objects and advantages of the invention will become apparent throughout the course of the following description:

In the accompanying drawings, wherein for the purpose of illustration is shown a 45 preferred embodiment of my invention, and wherein like reference characters designate like parts throughout:

Figure 1 is a plan view of a platen having my guide applied thereto;

50 Fig. 2 is a front elevation of the shiftable bar and guide rod;

Fig. 3 is a plan view thereof;

Fig. 4 is a section on the line 4-4 of Fig. 2;

Fig. 5 is a section of the line 5-5 of 55 Fig. 3, and

Fig. 6 is a section of the line 6-6 of Fig. 3.

Referring now more particularly to the drawings, the numeral 10 indicates the 60 platen of a press upon which the usual tympan T is held by the tympan bails 11. The platen 10 is provided at the lower side thereof with the usual gripper bar 12 upon which are adjustably mounted the usual grippers 65 13 which engage the sheet of paper P during the printing operation to hold the same. The numeral 14 indicates the usual shifting fork employed for positioning the sheet P against the guides G and against a side 70 guide which is usually employed but not herein shown. This fork is actuated by the gripper bar through medium of a feed fork swing 15 to which the fork 14 is secured. As is well known to those familiar with the 75 art, the movement of the gripper bar shifts the fork subsequently to the insertion therein of the sheet P causing the sheet to be moved against the side guide. The platen 10 is usually sufficiently inclined to cause 80 the sheet P to engage the stationary guides G which are secured to the tympan T in the usual manner.

In accordance with my invention, I mount upon the lower edge of the platen a bar 85 17 which embodies a body portion 18 provided with longitudinal slots 19. Through these slots 19 headed elements 20 extend and engage in the bed of the platen 10, the bar 17 being slidable upon the headed 90 elements. It will be understood that two of the bars 17 will be provided, one at each side of the platen with respect to the feed fork swing 15. Each of the bars 17 is provided upon the upper surface of the body 95 portion 18 thereof with a guide strip 21 having the form of a dove tail tongue. This strip may either be formed integrally with the body portion 18 or be secured thereto in any suitable manner, the form 100 of application being immaterial. The upper surface of the strip or tongue 21 is provided with graduations for a purpose presently to appear.

The inner ends of the bar 17 are provided with threaded apertures 22 adapted for the reception of a securing member 23 which securing member forms a pivotal mounting for one end of a tongue 24, the opposite end of which is pivotally connected as by means of a screw 25 to the fork receiving section 26 of the feed fork swing 15. From the foregoing it will be seen that when the feed fork swing actuates the feed fork, the connection between the swing 15 and the bar 17 will cause the same to be shifted longitudinally toward the feed fork swing. It will also be obvious that as the feed fork swing continues its movement after the feed fork has released the paper the bar 17 will continue its movement subsequently to the shifting of the paper by the feed fork.

The numeral 16 indicates a side guide rod which is mounted upon the bar 17 through medium of a head 27 provided with a dovetail groove 28 which slidably receives the tongue 21 of the bar 16. The rod 16 may be adjusted to any desired position upon the bar 17, the adjusted position being designated by the graduations upon the tongue 21 thereof and may be held in such adjusted position by means of the set screw S or some similar expedient. The graduations upon the tongue 21 will represent the distance from the edge or center of the platen as may be desired when the bar 17 has been shifted toward the center of the platen to its fullest extent by the feed fork swing 15. Slidably mounted upon the guide rod 16 is a side guide 30 which is provided in its side walls with openings 31 through which the rod 16 extends. The upper surface of the rod 16 is provided with transversely extending graduations, as indicated at 29, which coact with a spring 32 carried by the side guide to hold the side guide in adjusted position. The side guide is likewise provided in its side walls with a pair of aligned openings 33 which slidably receive a gage tongue 34 and hold the same in spaced relation to the tympan T. This gage tongue prevents the paper from jumping over the side guide. In the operation of my device, the paper is fed to the platen and upon the tympan R on a line approximately indicated by the character L and engages in the tines of the shifting fork 15. The normal action of the shifting fork tends to shift the paper to the line approximately indicated by the character M. The shifting of the swing 15, however, causes the bar 17 to shift longitudinally toward the center of the platen and, accordingly, to shift the guide rod 16 and guide 30 toward such center. The result is that the guide 30 engaging the paper moves the paper back to a line indicated by the letter N. This amount of shifting is made sufficient to overcome any bounce of the pa-

per away from the side guide under the impulse received from the fork 14, the paper being slid longitudinally through medium of the guide 30 and being positioned very readily.

From the foregoing it will be obvious that I have provided a tympan gage which will very accurately position the paper upon the tympan and which is automatic in its operation; and it will likewise be obvious that through the construction hereinbefore set forth the maximum adjustability of the side guide is rendered possible. It will furthermore be obvious that the construction as hereinbefore set forth is capable of many minor changes without in any manner departing from the spirit of my invention and I, accordingly, do not limit myself to such specific structure as hereinbefore set forth, except as limited by the sub-joined claims.

What I claim is:

1. The combination with a platen, shifting fork for shifting a sheet upon the platen, an actuating mechanism for the shifting fork, of a side gage against which the sheet is shifted by the shifting fork, and means for shifting the side gage to move the sheet in a direction opposite to the direction of movement imparted thereto by the shifting fork.

2. The combination with a platen, shifting fork for shifting a sheet upon the platen, an actuating mechanism upon the shifting fork, of a side gage against which the sheet is shifted by the shifting fork, and means actuated by the actuating mechanism for the shifting fork for shifting said side gage in a direction opposite to the direction of movement imparted to the sheet by the shifting fork.

3. The combination with a platen, shifting fork for shifting a sheet upon the platen, an actuating mechanism for the shifting fork, of a side gage and means actuated by the actuating mechanism for the shifting fork for shifting the said gage in a direction opposite the direction of movement imparted to the sheet by the shifting fork subsequently to the shifting thereto by said shifting fork.

4. In combination with a press embodying a platen, a gage, a sheet shifting fork operating upon the platen and operating to shift the sheet to be printed to engage said gage, of means for shifting the gage in a direction opposite to that in which the sheet is shifted by the shifting fork subsequently to its shifting by said shifting fork.

5. In combination with a press embodying a platen and a sheet shifting fork operating upon the platen and operating to shift the sheet to be printed in one direction and actuating means for said fork, of means actuated by said fork actuating means for shifting the sheet in a direction opposite to

- that in which it is shifted by the shifting fork subsequently to its shifting by said shifting fork.
6. The combination with a platen, of a bar 5 slidably mounted upon one edge thereof, a feed fork swing, a link connecting said feed fork swing and said bar, a guide rod adjustably mounted upon said bar and a side guide carried by said guide rod.
- 10 7. The combination with a platen, of a graduated bar slidably mounted upon one edge thereof, a feed fork, a swing therefor, a guide rod adjustably mounted upon said bar, the side guide adjustable upon said 15 guide rod, actuating means for said feed fork and means connecting said actuating means and said bar whereby said bar is shifted in a direction opposite to the swing of said feed fork.
- 20 8. The combination with a platen, of a graduated bar slidably mounted upon one edge thereof, a feed fork, a swing therefor, a guide rod adjustably mounted upon said bar, the side guide adjustable upon said 25 guide rod, actuating means for said feed fork and means connecting said actuating means and said bar whereby said bar is shifted in a direction opposite to the swing of said feed fork subsequently to the operative swing of said feed fork.
- 30 9. The combination with a platen and a feed fork adapted to shift a sheet upon the platen in one direction, of a slidably mounted bar, a guide adjustably mounted on the 35 bar, a side guide carried by said guide, and means for shifting said bar in a direction opposite to the direction of movement imparted to the sheet by said feed fork.
10. The combination with a platen and a 40 feed fork adapted to shift a sheet upon the platen in one direction, of a slidably mounted bar, a guide adjustably mounted on the bar, a side guide carried by said guide, and means for shifting said bar in a direction 45 opposite to the direction of movement imparted to the sheet by said feed fork subsequently to the shifting of the sheet by said feed fork.
11. The combination with a platen, of a bar slidably mounted upon one edge thereof, 50 a feed fork swing, a link connecting said feed fork swing and said bar, a guide rod adjustably mounted upon said bar, and side guide adjustably mounted upon the guide rod.
12. The combination with a tympan covered platen, a side guide slidably engaging the face of the tympan, a feed fork adapted to engage a sheet and shift the same to engage said side guide, and means for shifting 60 said side guide in a direction opposite to the direction of movement imparted to the sheet by the fork subsequently to the movement of the sheet by the fork.
13. The combination with a platen, a stop 65 associated with the platen and means for shifting a sheet in one direction upon the platen to engage the stop, of means operating subsequently to the first named means for shifting the sheet in the opposite direction.
14. The combination with a platen, of means for shifting the sheet upon the platen in one direction, means for subsequently shifting the sheet in the opposite direction 75 and common actuating mechanism for both of said means.
15. The combination with a platen, a stop associated with the platen and means for shifting a sheet upon the platen to engage 80 the stop, of means for shifting the stop subsequently to the shifting of the sheet in said direction to shift the sheet in the opposite direction.
16. The combination with a platen, a stop 85 associated with the platen and means for shifting a sheet upon the platen to engage the stop, of means for shifting the stop subsequently to the shifting of the sheet in said direction to shift the sheet in the opposite 90 direction, and common operating means for both of said sheet shifting means.

In testimony whereof I hereunto affix my signature.

JACOB S. MERKINS.
